UNITED STATES PATENT OFFICE.

WILLIAM L. RODGERS, OF PITTSBURGH, PENNSYLVANIA.

OSCILLATING WASHING MACHINE.

Application filed October 7, 1922. Serial No. 593,019.

To all whom it may concern:

Be it known that I, WILLIAM L. RODGERS, a citizen of the United States, and a resident of Pittsburgh, in the county of Allegheny and State of Pennsylvania, have invented a new and useful Improvement in Oscillating Washing Machines, of which the following is a specification.

This invention relates to washing machines and particularly to an improved driving gearing and locking means for the oscillating tub used in connection therewith.

The object of the invention is to provide a gearing and locking means adapted for this purpose which is simple and compact in its arrangement, which is entirely mounted in the gear housing or casing, such housing or casing being preferably formed as a unit which may be readily attached to or removed from the frame of the machine.

It is also an object of the invention to provide a gearing which may be mounted in a unitary housing and as a unit upon a single side member of the frame so as to position all of the driving mechanism and actuating devices to be used in connection with the machine in one convenient location.

In washing machines of the oscillating tub type, great difficulty has been experienced due to the easy and unexpected tilting of the tub while the same is disconnected from its driving gearing. This difficulty is particularly objectionable during the filling of the tub with hot water, and also when the clothes which have been washed are removed from the tub and passed through the wringer located above. Unexpected tilting of the tub during the filling or emptying thereof frequently causes splashing or the spilling of hot water upon the operative.

It is a special object of the invention to provide a driving gearing for oscillating tubs of washing machines, having means for positively locking the tub against rocking movement when disconnected from its driving gearing, and in which a single moving element of the gearing will function to selectively oscillate the tub or lock it against oscillation, and when in its locked condition to retain the tub with its opening in an upright position to facilitate safe and rapid filling with water, or removing the clothes which are then passed through the wringer located above.

These and other objects of the invention

will more readily appear when taken in connection with the following description and the appended claims.

In the accompanying drawings, Fig. 1 is a side elevation of a washing machine equipped with the invention, illustrating the position of the oscillating tub while in locked condition; Fig. 2 an enlarged detail view, with parts broken away, of the gear housing removed from the frame; Fig. 3 a fragmentary detail sectional view taken on the line III—III of Fig. 2, illustrating the position which the parts assume during the oscillation of the tub; and Fig. 4 a fragmentary detail view showing the positions which the parts assume for locking the tub against oscillation.

The supporting frame of the machine comprises side frame members 1, 2 and the end members 3 and 4, the several members of the frame being rigidly secured to each other by means of rivets indicated at 5. All of the frame members are preferably constructed of sheet metal and, for conveniently supporting the several parts and at the same time affording access thereto, are shaped, as clearly shown in the drawings, the side member 2 being provided with a recess at 6 adjacent the lower portion thereof for the purpose of permitting ready access to the driving motor and the connections between the same and the gearing proper. Spanning the space between the end frame members 3 and 4 is a transverse bar 7 which, together with an angle bracket 8 and a suitable base or platform, serve to support the driving motor 9. Preferably the motor employed is an electric motor, but it is obvious that any type of motor suitable for the purpose may be employed, the armature shaft of the motor 9 being connected through well known flexible couplings or equivalent devices with the inner extremity of the main driving shaft 10.

Removably attached to the exterior of the side frame member 1 is a gear housing or casing designated as a whole by the reference numeral 11 which housing encloses all of the parts comprising the gearing and serves as a means in which to journal the several parts thereof, the entire housing with its contained gearing being removable from the side frame member and machine as a unit, the housing being attached to the frame by means of suitable bolts fitting into bosses formed upon the housing as clearly indicated in the

drawings. The outer open side of the housing 11 is provided with a cover plate 12 on which a bearing boss 13 is formed in alignment with the outer extremity of the shaft 10, and in which the extremity of the shaft is journalled. The shaft 10 is operatively connected through any suitable gearing adapted to reciprocate the connecting rod 14 which is operatively connected to the crank arm 15 by means of the pin 15'.

The crank arm 15 is loosely mounted upon a rock shaft 16 journalled in a bearing boss 17 formed upon the bottom of the housing 11 and a specially formed bearing bushing 18 suitably attached to the cover plate 12, the inner extremity of the rock shaft having fixed thereto the trunnion block supporting arm 19 which is in the form of a crank arm provided with a longitudinal slot extending substantially the full length thereof and a stop lug 20 adjacent its extreme end. The slot of the trunnion supporting arm is adapted to receive a suitably shaped trunnion block 21 projecting from the spider 22 attached to one side of the oscillating tub 23, the block 21 merely projecting within the slot of the member 19 and resting upon the stop lug 20 so as to render the same readily removable therefrom upon bodily lifting the tub from the frame in an obvious manner. The tub 23 corresponds in general construction to those in common use, being provided with a filling opening at its upper portion 24. The bearing boss 17 projects through an opening 25 formed in the side frame member 1, the said opening being of such dimensions as to permit the ready removal of the trunnion block supporting arm 19 therethrough.

The bearing bushing 18 is cup-shaped with its reduced outer cylindrical portion projecting through an opening 26 formed in the cover plate 12, the enlarged inner portion of the bushing being secured to the cover plate in any desirable manner as by riveting. The inner face of the bushing is provided with recesses 27, 27' which are disposed at opposite sides of the rock shaft when the parts are in assembled relation, the rock shaft being journalled in the bushing 18, as above described, by projecting the outer cylindrical portion 28 of the shaft within the axial bore of the reduced cylindrical portion of the bushing, a space 29 being left between the outer end of the rock shaft and the bottom of the bore for the purpose of holding a lubricant which may be fed thereto through the aperture 30. The intermediate portion 31 of the rock shaft 16 between its inner extremity upon which the crank arm 15 is mounted and its outer cylindrical portion 28 is non-circular in cross section. Mounted for free sliding movement upon the non-circular intermediate portion of the shaft but rotatable there-

with is a clutch collar 32 provided with the peripheral groove 33, and lugs 34, 34', and 35, 35' formed respectively upon the opposite faces thereof. The lugs 34, 34' are adapted to project into suitably formed recesses 36, 36', in the adjacent faces of the crank arm 15, while the lugs 35, 35' are adapted to be received by the recesses 27, 27' formed in the bearing bushing 18.

The clutch collar 32 is adapted to be shifted longitudinally along the non-circular portion 31 of the rock shaft by suitable clutch shifting mechanism, this mechanism comprising an actuating handle 37 fixed to the outer extremity of a rotatable shaft 38 journalled in the side of the housing 11, a crank arm 39 being formed at the inner extremity of the shaft 38 and provided with a finger 40 which projects into the peripheral slot 33 of the clutch collar. In order to retain the clutch shifting mechanism in a position to either hold the lugs of the clutch collar in engagement or out of engagement with the recesses formed in the crank arm and bearing bushing, a spring pressed pin 41 adapted to seat in suitable depressions in a plate 42 is employed.

Mounted upon the side frame member 1 at one side of the gear housing 11 so as to be within easy reach of the operator in actuating either the clutch handle 37 or the controlling elements of the wringer mechanism (not shown) is a switch 43 for starting and stopping the electric motor 9.

The operation of the device is as follows: The shaft 10 is driven by the motor 9 and transmits power through suitable operative connections, as above described, causing reciprocation of the connecting rod 14, and in turn rocking the crank arm 15 about the rock shaft 16 as an axis. If the clutch collar 32 is in a neutral position in which neither sets of lugs are in engagement with their respective recesses formed in the crank arm 15 or the bearing bushing 18, no power will be transmitted to the rock shaft which may be freely oscillated together with the tub 23, if so desired. Whenever the clutch collar 32 is moved to the position shown in Fig. 3, with the lugs 35, 35' in engagement with the recesses 36, 36', rocking movement of the crank arm 15 will be communicated to the rock shaft 16, consequently causing oscillation of the tub 23 in an obvious manner. Whenever it is desirable to lock the tub 23 against oscillating movement, the clutch collar 32 is shifted to its extreme outer position, illustrated in Fig. 4, at which time the lugs 35, 35' engage the recesses 27, 27' in the bearing bushing 18, positively preventing oscillation of the rock shaft 16 and the tub 23. The lugs formed upon the clutch collar and the recesses with which the lugs engage are so positioned that when the parts are moved into the locked condition, just de-

scribed, the filling opening at the top of the tub will be in its uppermost position.

The trunnion receiving crank arm 19 is attached to the rock shaft 16 so as to normally project downwardly, and is urged to its vertical position under the influence of gravity due to its own weight. This disposition of the crank arm 19 together with the peculiar construction thereof for receiving the trunnion block 21, permits the ready removal of the tub 23 by merely lifting the same vertically upwardly. Due to the fact that the opening 25 in the side frame member 1 is of such dimension as to permit the crank arm 19 to be easily withdrawn therethrough, in conjunction with the removable mounting of the gear housing 11 upon the side frame member, enables the gear housing with its contained gearing to be easily detached from the machine, after the tub 23 has been removed in the manner described, for purposes of replacement or repair.

It is thus seen that the invention provides a driving gearing for washing machines of the oscillating type which is simple in construction, compact, durable, economical to manufacture and repair, all parts of which are readily accessible, one which may be easily attached to and removed from the machine as a unit, and which will positively and effectively function to set the tub in oscillation or retain the same in locked condition with its filling opening in uppermost position.

Although the preferred embodiment of the invention has been particularly illustrated and described as required by the patent statutes, it is obvious that many changes in details of construction in the several parts may be made without departing from the spirit of the invention, and is therefore not intended to limit the invention beyond that particularly pointed out and defined in the appended claims.

I claim:

1. A gearing for oscillating washing machines comprising a housing, a cover plate for said housing, a separately formed bearing bushing fixed to the cover plate provided with recesses in its inner face, a rock shaft supported in the housing having one end journaled in said bushing, a crank arm loosely mounted on said shaft, said shaft being non-circular in cross section throughout its intermediate portion within the interior of the housing, the said crank arm having recesses upon its inner face, a clutch collar shiftable upon the non-circular portion of

the shaft but rotatable therewith, lugs on the opposite faces of the clutch collar for selectively engaging the recesses in either the crank arm or the bushing, and means for shifting the said collar.

2. A gearing for oscillating washing machines comprising a housing, a cover plate for said housing having an opening extending therethrough and a depression on its inner face surrounding the said opening, a separately formed bearing bushing equipped with enlarged and reduced portions fixed to the cover plate and provided with recesses in its inner face, the said enlarged portion being positioned within the said depression and the reduced portion extending through the said opening, a rock shaft supported in the housing having one end journaled in said bushing, a crank arm loosely mounted on said shaft, said shaft being polygonal in cross section throughout its intermediate portion within the interior of the housing, the said crank arm having recesses upon its inner face, a clutch collar shiftable upon the polygonal portion of the shaft but rotatable therewith, lugs on the faces of the clutch collar for selectively engaging the recesses in either the crank arm or the bushing, and means for shifting the said collar.

3. In combination in an oscillating washing machine, a supporting frame, a housing attached to said frame equipped with a cover plate, a separately formed bushing fixed to the cover plate provided with recesses in its inner face, a rock shaft supported in the housing having one end journaled in said bushing, an oscillating tub fixed to the opposite end of the rock shaft, said tub having a filling opening at its top, driving means for oscillating said rock shaft including a crank arm having recesses on its face journaled on the rock shaft, said shaft being non-circular in cross section throughout its intermediate portion, a clutch collar shiftable upon said non-circular portion of the rock shaft but rotatable therewith, lugs on the opposite faces of the clutch collar for selectively engaging the recesses in either the crank arm or the bushing, and means for shifting the said collar, the recesses in the bushing being disposed whereby engagement of the lugs on the clutch collar with the recesses in the bushing will lock the rock shaft and tub against oscillation with the filling opening of the tub in its uppermost position.

In testimony whereof, I sign my name.

WILLIAM L. RODGERS.
